UNITED STATES PATENT OFFICE.

FRANK A. WEISS, OF PHILADELPHIA, PENNSYLVANIA, ASSIGNOR TO THE BELBER TRUNK & BAG COMPANY, OF PHILADELPHIA, PENNSYLVANIA, A CORPORATION OF PENNSYLVANIA.

DESIGN FOR A DOWEL-BOLT FOR TRUNKS.

52,595.

Specification for Design.

Patented Oct. 15, 1918.

Application filed February 8, 1918. Serial No. 216,118. Term of patent 14 years.

To all whom it may concern:

Be it known that I, FRANK A. WEISS, a citizen of the United States, residing in the city and county of Philadelphia and State of Pennsylvania, have invented a new, original, and ornamental Design for a Dowel-Bolt for Trunks, of which the following is a specification, reference being had to the accompanying drawing, which forms a part thereof.

The figure is a face view of the two members of the dowel bolt, which comprises two base plates on which are respectively mounted the two mutually engaging bolt members. One of the bolt members comprises three transversely extending elements, the upper and lower of which are relatively wide and are united to the middle transverse element by upright connecting elements; all the elements having the partial tubular shape indicated: The other bolt

member comprises three transverse elements (similar in configuration to the three transverse elements of the first bolt member), the upper and lower rear portions of which are curved respectively downward and upward and thence forward so as to merge into the middle transverse element and into each other.

The bolt members, when approximated, have a general resemblance to the letter **B**.

I claim:

The ornamental design for a dowel bolt for trunks, as shown and described.

In testimony of which invention, I have hereunto set my hand, at Philadelphia, Pa., on this 2nd day of February, A. D. 1918.

FRANK A. WEISS.

Witnesses:

E. W. HAWLEY,
CATHERINE E. MAGUIRE.
